Philip R. Horwitch, Leominster, Mass., assignor to Paramount Manufacturing Company, Leominster, Mass., a corporation of Massachusetts

Application May 22, 1952, Serial No. 19,835

Term of patent 14 years

(Cl. D74—1)

To all whom it may concern:

Be it known that I, Philip R. Horwitch, a citizen of the United States residing in Leominster, in the county of Worcester and State of Massachusetts, have invented a new, original, and ornamental Design for a Combined Letter Opener and Pencil, of which the following is a specification, reference being had to the accompanying drawing, forming a part thereof, in which:

Figure 1 is a front elevational view of a combined letter opener and pencil, showing my new design;

Figure 2 is a rear elevational view of the combined letter opener and pencil, and,

Figure 3 is a side elevation thereof.

Figure 4 is a cross sectional view thereof, taken on the line 4—4 of Figure 2.

I claim:

The ornamental design for a combined letter opener and pencil, as shown.

PHILIP R. HORWITCH.
